UNITED STATES PATENT OFFICE.

FRED HOLMES REES, OF ELMIRA, NEW YORK.

STATION-INDICATOR.

SPECIFICATION forming part of Letters Patent No. 650,951, dated June 5, 1900.

Application filed August 9, 1899. Serial No. 726,689. (No model.)

To all whom it may concern:

Be it known that I, FRED HOLMES REES, a resident of Elmira, in the county of Chemung and State of New York, have invented certain new and useful Improvements in Station-Indicators; and I do hereby declare the following to be a full, clear, and exact description of the invention, such as will enable others skilled in the art to which it pertains to make and use the same.

The invention relates to station-indicators and like devices; and its object is to increase the efficiency and certainty of their action and to simplify the construction.

15 The invention consists in the construction hereinafter described and pointed out.

Figure 1 is a broken perspective of a station-indicator. Fig. 2 is an elevation of the mechanism. Fig. 3 is an elevation of roller-driving devices. Figs. 4 and 5 are opposite end elevations of the same. Fig. 6 is a section of a gear, spring, and inclosing cap; and Fig. 7 is a broken elevation of a modification.

25 Numeral 1 denotes a case of any usual or desired form, and 2 is a window, which may be glazed or not. In practice when used as a station-indicator I prefer to place the words "Next station" above the opening which discloses said stations, as shown in the drawings.

30 3 and 4 are rollers, and 5 is a band marked to indicate stations or other matters. The rollers are provided with gears 6 and 7 on their respective shafts and adapted to coöperate by means of a pinion 8.

35 9 indicates a supporting-plate or post fixed in the case and in which the roller-shafts have bearings.

To the shaft of roller 4 are fixed two ratchet-wheels 10 and 11, with their teeth facing opposite, as shown, whereby the wheels are adapted to be oppositely driven.

40 12 denotes a bar pivotally supported at 13 by an arm 14, loose on the shaft of roller 4 and held in place lengthwise the shaft by a washer and spring-pin.

45 15 and 16 denote pawls carried by the bar and situated in the planes of the respective ratchet-wheels. As shown, pawls 15 can be made to engage the teeth 15' of wheel 10 and the pawl 16 the teeth 16' of wheel 11. It is not, however, essential that these wheels be

separate, nor that the teeth be arranged in separate planes. The construction indicated in the drawings, comprising two toothed disks which are identical in form, though oppositely situated as respects their teeth, is a convenient and economical construction and is preferred.

The bar 12 and the arm 14 constitute a lever which rocks on the shaft whenever either 60 chain 17 is suitably manipulated to drive a ratchet-wheel by means of a pawl.

18 denotes a pawl-returning spring having one end fixed to the arm 14 and the other fixed to the plate 9 or other suitable support. 65

By this construction the indicator-band can be wound in either direction indefinitely and its direction reversed at any desired point. Both pawls are normally held out of the path of the ratchet-teeth, but in readiness to operate immediately whichever chain is manipulated.

The shaft of roller 4 has an angular part 4', upon which bears a spring 19, which arrests the rollers as soon as the chain which 75 drives them by means of the pawl and ratchet is released. The faces of said part 4' of the shaft may be of any desired number and are properly proportioned to coöperate with the spring to arrest the rollers when the ratchet-teeth are in suitable situation to be immediately engaged by a forwardly-moving pawl.

To take up the slack of the band and also provide for tension at other times, the gear 3 is provided with a recess or chamber 3', and in said chamber is placed a tension-spring 20, constituting the operative connection between said wheel and its shaft, one end of the spring being secured to the shaft and the other to the wheel. 90

21 denotes a cap to cover the spring-chamber, provided with a tubular boss 22, coöperating with a similar boss 23 on the opposite side of the wheel to give a wide bearing between the wheel and shaft. 95

24 denotes screws for fastening the cap to the wheel. The spring is accessible for varying its tension or for renewal.

The preferred form of spring-holding chamber is shown in Fig. 6, in which the spring is 100 inclosed between a face of the gear and a cap 25, having a shoulder 3".

Having thus described my invention, what I claim as new, and desire to secure by Letters Patent, is—

1. In combination with rollers for indicators or the like, gears operatively connecting the rollers, a reversely-acting wheel-ratchet fixed to a roller-shaft, an oscillating pawl-lever carrying a driving-pawl for each of two ratchets, and a spring normally holding both pawls out of the path of the ratchet teeth, said spring being secured to the lever and to a fixed point.
2. In combination with rollers for indicators or the like, gears operatively connecting the rollers, one of said gears having a spring connection with one of the rollers, a reversely-acting wheel-ratchet fixed to a roller-shaft, an oscillating pawl-lever carrying a driving-pawl for each of two ratchets, and a spring normally holding both pawls out of the path of the ratchet-teeth, said spring being secured to the lever and to a fixed point.
3. A compound ratchet-wheel comprising two disks fixed to each other and having oppositely-arranged teeth and a lever opera-

tively carrying pawls to engage the oppositely-situated teeth of the disks, said pawls being pivotally secured to the lever and lying normally out of engagement with the teeth of the disks.

4. In combination with rollers for indicators or the like, gears operatively connecting the rollers, one of said gears being recessed and having a spring secured in said recess forming a connection between the gear and one of the rollers, a reversely-acting wheel-ratchet fixed to a roller-shaft, an oscillating pawl-lever carrying a driving-pawl for each of two ratchets, and a spring normally holding both pawls out of the path of the ratchet-teeth, said spring being secured to the lever and to a fixed point.

In testimony whereof I have signed this specification in the presence of two subscribing witnesses.

FRED HOLMES REES.
